(57) **CLAIM**

The ornamental design for a painters' palette, as shown and described.

DESCRIPTION

The patent or application file contains at least one drawing executed in color. Copies of this patent or patent application publication with color drawing(s) will be provided by the Office upon request and payment of the necessary fee.

1. Painters' palette
2. Painters' palette
4. Part of painters' palette
- 1.1 : Perspective
- 1.2 : Perspective
- 1.3 : Front
- 1.4 : Right
- 1.5 : Top
- 1.6 : Bottom
- 1.7 : Exploded
- 2.1 : Perspective
- 2.2 : Enlarged
- 2.3 : Enlarged
- 2.4 : Perspective
- 2.5 : Enlarged
- 2.6 : Enlarged
- 2.7 : Front
- 2.8 : Right
- 2.9 : Top
- 2.10 : Bottom
- 2.11 : Exploded
- 2.12 : Perspective
- 4.1: Perspective
- 4.2: Perspective
- 4.3 : Front
- 4.4 : Right
- 4.5 : Top
- 4.6 : Bottom
- 4.7 : Exploded
- 4.8 : Exploded

Reproductions 2.2 and 2.3 are enlarged views of reproduction 2.1; reproductions 2.5 and 2.6 are enlarged views of reproduction 2.4; reproduction 2.12 shows an accessory (highlighted in green color). Features shown in the color green represent environment and form no part of the claimed design.

1 Claim, 27 Drawing Sheets
